UNITED STATES PATENT OFFICE.

FRIEDMAN STERNHEIMER, OF NEW YORK, N. Y.

FAN.

SPECIFICATION forming part of Letters Patent No. 297,869, dated April 29, 1884.

Application filed March 8, 1884. (No model.)

To all whom it may concern:

Be it known that I, FRIEDMAN STERNHEIMER, of the city, county, and State of New York, have invented certain new and useful Improvements in Fans, of which the following is a specification.

This invention has reference to an improved fan that can be conveniently folded up and carried in the pocket; and the invention consists of a fan composed of a middle section attached to the handle, and two hinged and folding side sections, to which a natural spring is imparted by means of a connecting flexible foundation-piece. The natural spring is re-enforced by an elastic cord applied to buttons of the middle and folding side sections. A locking device applied to the handle retains the side sections in folded position.

20 In the accompanying drawings, Figures 1 and 2 represent side views of my improved fan, showing the same from opposite sides. Fig. 3 is a side view of the fan, showing the same in folded position. Figs. 4 and 5 are horizontal sections taken, respectively, on lines $x x$, Fig. 2, and $y y$, Fig. 4; and Fig. 6 is a vertical transverse section of the web of the fan on line $z z$, Fig. 1.

Similar letters of reference indicate corresponding parts.

A in the drawings represents the middle section of the web of my improved fan, and B B the side sections of the same, which are hinged to the middle section and adapted to be folded over the same. The middle section, 35 A, is attached to a handle, C, to the shank of which a spring-clasp, D, of any approved construction, is applied. The spring-clasp D serves for the purpose of locking the hinged sections B B in folded position on the middle section, as shown in Fig. 3. On opening the spring-lock D the folded side sections, B B, are thrown by their natural spring into open position. This natural spring is obtained by 40 pasting the middle and side sections, A and B B, of the web to a flexible foundation-piece, E, which also forms the hinge-connection of the side sections with the middle section. The foundation-piece E imparts in drying a slight

warp to the sections A and B B, so that they 50 are slightly convex at one side and slightly concave at the other side, as shown in Fig. 6. By folding the hinged sections B B over the middle section, A, a certain degree of tension is exerted at their ends on the hinge-connection of these sections, so that they are returned instantly into open position when released. To prevent the wearing out of this natural spring of the hinged side sections, B B, it is preferable to employ as an auxiliary 60 spring a loop-shaped elastic band or cord, F, which is detachably applied to buttons f of the middle and side sections, A and B B, as shown in Figs. 1 and 3. This spring band or cord re-enforces the natural spring of the side 65 sections, and may be readily replaced when worn out by a new loop.

When the fan is in open position for use, the spring-clasp D may be used to advantage to hold a programme, order of dancing, or 70 other device, as shown in Fig. 2. When the fan is folded up, it may be conveniently carried in the pocket or stored away.

The fan can be finished so as to present a neat and ornamental appearance.

Having thus described my invention, I claim as new and desire to secure by Letters Patent—

1. The combination, in a fan, of a middle web-section, having a fixed handle, and hinged side sections, the middle and side sections being applied to a flexible connecting foundation-piece, whereby a natural spring is imparted to said web-sections, substantially as set forth.

2. The combination of the middle web-section having a handle, hinged side sections, a connecting flexible foundation-piece, that imparts a natural spring to the web-sections, and means whereby the side sections are held in folded position on the fan, substantially as set forth.

3. The combination of the middle section, A, having a handle, C, and spring-clasp D, with hinged side sections, B B, to which a natural spring is imparted by being applied 95 to a flexible foundation-piece, E, substantially as set forth.

4. The combination, with the middle sec-

tion, A, having a handle, C, and a spring-clasp, D, of hinged side sections, B B, a flexible foundation-piece, E, and an elastic loop or band, F, attached to the convex sides of 5 the web-sections A and B B, so as to re-enforce the natural spring of the fan, substantially as set forth.

In testimony that I claim the foregoing as my invention I have signed my name in presence of two subscribing witnesses.

FRIEDMAN STERNHEIMER.
